UNITED STATES PATENT OFFICE.

LERoy L. RICHARD, OF COALINGA, CALIFORNIA.

PIPE, CASING, AND DRILL-STEM TONGS.

1,259,670.

Specification of Letters Patent. Patented Mar. 19, 1918.

Application filed July 24, 1917. Serial No. 182,445.

To all whom it may concern:

Be it known that I, LEROY L. RICHARD, a citizen of the United States, residing at Coalinga, in the county of Fresno and State 5 of California, have invented certain new and useful Improvements in Pipe, Casing, and Drill-Stem Tongs, of which the following is a specification.

My invention relates to the class of tongs 10 adapted, in general, for setting up and unscrewing the joints of pipe.

The invention is, however, especially intended for use in the well-drilling art, and it may be used upon well casing, though I 15 particularly design the tongs for the making and breaking of the rotary-tool joints of the drill-stems.

In rotary well-drilling apparatus, the drill is carried on the lower end of a drill stem, 20 which consists of a string of pipe sections, several of which, termed a "stand" are directly screwed together; and these stands are successively united by rotary-tool joints composed of a male and female member 25 screwed together.

The drill stem, in being lengthened, and in being dismembered on removal, is usually broken at these tool joints into its several stands. In this operation it is usual to employ 30 two men on the derrick floor, one man operating one pair of tongs, to effect the screwing or unscrewing of the joint, and the other man operating another pair of tongs called the "back up" tongs, to hold the joint 35 against the pressure of the first tongs. In this operation much time and labor are consumed in fitting and manipulating the two pairs of tongs, these being suspended from the derrick and fitted with pull and pull- 40 back attachments, requiring adjustment and attention. These are well known operations and need no detailed description, in order to fully understand the objects and advantages of my invention.

The essential object I have in view is to 45 provide a single tool or instrument capable in itself of serving both as a pressure and a back-up tongs, thereby avoiding the necessity of two independent and separate tongs, 50 and dispensing with one man on the derrick floor,

A further object is to adapt the tool for ready application without the use of latches, and the loss of time in their manipulation.

In the special application of my tongs, 55 namely, to the rotary-tool joints of drill-stems, no consideration need be paid to the common idea that the jaws must fully encircle the pipe in order to avoid a crushing effect, because the joints in question are 60 quite thick and are not liable to be crushed. Therefore, the jaws of my tongs but partially embrace the joint members, and can be readily snapped to place, requiring no latches. I have, however, provided supplementary jaws to be used in connection with the main jaws in such manner that they too 65 can be readily fitted to and approximately fully encircle the pipe without the necessity of latching, thereby adapting the tool for 70 any kind of pipe, or for well-casing, or for screwing up or unscrewing the stem sections, both of the "stand," and where said sections join the tool-joint.

To these ends my invention consists in 75 the novel tongs which I shall now fully describe, by reference to the accompanying drawings, in which—

Figure 1 is a front elevation of my tongs.

Fig. 2 is a top-plan of the same. 80

Fig. 3 is a vertical section on the line 3—3 of Fig. 2.

Fig. 4 is a horizontal section on the line 4—4 of Fig. 1.

Fig. 5 is a horizontal section on the line 5—5 of Fig. 1. 85

Fig. 6 is a front elevation of a slight modification of my tongs, with respect to the transmission of the handle movement to the jaws and dogs. 90

Fig. 7 is a horizontal section on the line 7—7 of Fig. 6.

Fig. 8 is a front elevation of another modification involving a pinion and rack transmission from the handle to the jaws 95 and dogs.

Fig. 9 is a vertical section on the line 9—9 of Fig. 8.

Fig. 10 is a horizontal section on the line 10—10 of Fig. 9. 100

Fig. 11 is a plan view of the modification of Figs. 8 to 10 showing the attachment to

the tongs of a pair of supplementary jaws, the latter being in their inner or functional position.

Fig. 12 is a plan view of the tongs of Figs. 5 1-5 showing it in position ready for snapping on the rotary-tool joint.

Fig. 13 is an elevation of a rotary-tool joint showing the tongs applied thereto.

Fig. 14 is a plan view of the same.

10 Fig. 15 is a plan view of the tongs fitted with a pair of supplementary jaws, the latter being open and ready to be fitted to the pipe section of the rotary-tool joint.

15 Fig. 16 is an elevation of a rotary-tool joint with its pipe section, showing the tongs fitted to it.

Fig. 17 is a plan view of the same.

Referring particularly to Figs. 1 to 5, 1 is the body block or stock which carries the 20 operative parts. This block is arcuate, as seen in Fig. 4, on a radius adapting it to conform to the pipe, casing, stem or other part to which the tool is to be applied.

Upon the upper face of the block is slidably mounted, as, for example, by a dovetail 2, the upper or, as it may be termed, the pressure jaw 3, which is a channel member, approximately semicircular as to length, as seen in Figs. 2 and 4, on the same radius 30 as the arcuate block, upon which it slides in a circular path.

In each extremity of the jaw 3 is pivoted, by a pin 4, a gripping dog 5, the arcuate shank 6 of which is housed within the 35 jaw, the two shanks extending toward but spaced from each other.

A second jaw 3' which may be termed the "back-up" jaw is slidably mounted upon the lower face of the body block 1 as by a 40 dove tail 2', and in the extremities of said jaw are pivoted, by pins 4', the gripping dogs 5', with arcuate shanks 6'. The jaws, and dogs above and below are alike.

From the back center of the body-block 45 1 projects a shaft 7, upon which is pivoted a handle 8. Above the pivotal point, the handle carries a lug 9 which projects into the space between the adjacent extremities of the shanks 6 of the upper dogs 5; and 50 below said pivotal point, the handle carries a lug 9' which projects into the space between the adjacent extremities of the shanks 6' of the lower dogs 5'.

10 is a lock-pin for either of the upper 55 dogs and 10' is a similar lock-pin for either of the lower dogs. These pins are removably fitted through the jaw walls and the intervening dog-shanks. When so fitted, the dogs to which the pins are applied are 60 locked against movement on their pivot pins, while the other dogs are free to move on their pins.

The parts thus far described constitute the essential features of the tongs, and it

will be well, at this point, to describe their 65 operation and effect, before passing on to certain elaborations of the tool.

I shall describe the operation in connection with the ordinary rotary-tool joint of a drill-stem. In this joint, as shown in Fig. 70 13, 11 is the male member and 12 is the female member screwed together tightly. The tongs when in normal condition ready for application to the joint, as shown in Figs. 1 and 12, has its handle 8 vertical; 75 its lugs 9 and 9' aligned vertically; its jaws 3 and 3' symmetrically centrally disposed on the body block 1; and the gripping dogs 5 and 5' with their shanks 6 and 6' generally conform to and continue the curvature 80 of the jaws. The jaws and the dogs thus present an approximate semicircle and are adapted to be readily swung to and snapped upon the joint and to embrace the members thereof, as seen in Fig. 14. The upper or 85 pressure jaw with its dogs partially embrace the male member 11 of the joint and the lower or back-up jaw with its dogs partially embrace the female member 12 of the joint, as seen in Fig. 13. 90

Assuming the joint to be set up tight, and the object be to break and unscrew it, the lock-pin 10 is fitted, as seen in Figs. 1, 12 and 14, to lock the right hand upper dog (looking into the face of the tool), while 95 the left hand upper dog is free to swing on its pivot pin 4. Conversely, the lock-pin 10' is fitted to lock the left hand lower dog, leaving the right hand lower dog free to swing on its pivot pin 4'. 100

Now, by swinging the top of the handle 8 over to the left, its upper lug 9 moves over to contact with the extremity of the free shank 6 of the upper left hand dog 5, with the effect of throwing the shank backwardly and turning the dog itself inwardly into gripping contact with the male member 11 of the joint. The same movement of the handle 8 causes its lower lug 9' to move in the opposite direction to that of the upper lug 9, thereby bringing said lower lug into contact with the extremity of the free shank 6' of the lower right hand dog 5', and by swinging said shank backwardly, forces said dog into gripping contact with the female member 12 of the stem-joint. Continued movement in the same direction of the handle 8 now has the effect of relatively moving the two jaws on the body block, which movement theoretically would be equal in 110 opposite directions; but practically the movement is such that the jaw encountering the least resistance will move its applied member, while the other serves as a back-up on its member. Assuming, therefore, 115 that the male member 11 of the joint will give first, the upper jaw will turn said member in the direction to unscrew it, as shown

120
125

by the arrow in Fig. 13, while the lower jaw will hold on the female member as a back-up.

This first movement of the handle will, therefore, break the initial and hardest friction of the joint, and, to continue the unscrewing for a turn or two until the joint is sufficiently loose to be unscrewed by more convenient means, it is only necessary to move the handle 8 back again and over to the right of the vertical, so that its lugs 9 and 9' will work against the locked upper and lower dog shanks, whereupon the movement of the jaws will be reversed, all the dogs slipping in this direction to a fresh place, when the first movement may be repeated in order to continue the unscrewing effect. It will now readily be seen that if the object be to screw up instead of to unscrew the joint, it is only necessary to reverse the positions of the lock-pins 10 and 10', so that the upper dog which before was locked is now freed, and the upper dog which before was free is now locked; and so, likewise, with the lower dogs.

It may be required at times to unscrew the section of the drill stem from the joint. To adapt the device for this purpose, having in view the fact that the section is of smaller diameter, as shown by 13 in Fig. 16, than the tool-joint members, I provide the following attachment. 14, in Figs. 15, 16 and 17, is a pair of supplementary jaws. These are pivoted at 15 in the slotted ends of the upper dogs 5. They are arcuate on a radius adapting them for concentric housing within the main jaw, lying against the shanks of the dogs, as in Fig. 17; and their length is such that when so housed they will embrace the stem section, as seen in said Fig. 17 and in Fig. 16. In their open extended position, as in Fig. 15, they present a space to admit the stem section 13, and as they are pressed upon by it, they turn inwardly into the main jaw and finally embrace the section, fitting it closely. They have teeth 16, and as they lie against the shanks of the dogs, the operations heretofore described affect them to alternately grip and slip the stem section, while the lower main jaw with its dogs, serves as a back-up on the male member 11 of the joint to which it is applied.

These supplementary jaws by approximately encircling the pipe, also take care of the prevailing impression that the pipe must not be crushed by a partial grip. An extension of this idea naturally leads to the obvious fact that such supplementary jaws may be applied to the dogs of the lower main jaw as well as, and in addition to the upper main jaw, and thus make the tongs serve for unscrewing the joints of casing or other pipes. I have sufficiently indicated this by showing the lower dogs with slotted extremities adapted for the reception of

supplementary jaws like 14. It is also apparent that by varying the size and shape of these supplementary jaws various diameters of pipe may be worked on with the implement.

I shall now refer to slight modifications relating to the means for transmitting the movement of the handle 8 to operate the jaws and dogs.

In Figs. 6 and 7, the lugs 9 and 9' of the handle 8 instead of playing directly between and in contact with the adjacent ends of the dog shanks, are fitted in blocks 17 and 17' slidably mounted in the upper and lower jaws 3 and 3' respectively. These blocks contact with and act upon the dog shanks 6 and 6' respectively.

In Figs. 8, 9 and 10, the body member is in the form of a housing 18, in which the upper and lower jaws 3 and 3' slide by a tongue and groove connection shown at 19 in Fig. 9. In the jaws are slidably fitted the blocks 20, which like the blocks 17 of Figs. 6 and 7, play between and act on the shanks of the dogs carried by the jaws. These blocks have racks 21, with which engages a pinion 22 carried by a pin 23 of the handle 8, which is pivotally mounted on the back of the body housing 18.

In Fig. 1, 24 is the eye by which the tongs are suspended and counterbalanced from the derrick, and 25 in Figs. 2 and 5 is the eye for the pull back connection. In Fig. 1, 26 are the holes in the handle for the jerk line and the pull back.

I claim:

1. A tongs comprising a body-member; upper and lower jaws independently slidably mounted on said member; a gripping dog pivotally mounted and relatively opposite on each jaw; a fixed abutment in each jaw opposing its gripping dog; a handle pivotally mounted on the body-member; and means for transmitting the movement of the handle in one direction to simultaneously set in to gripping function the dogs of each jaw and to move said jaws in relatively opposite directions, and in the reverse direction of the handle to act against the fixed abutments to move the jaws and slip the dogs in relatively opposite reverse directions.

2. A tongs comprising a body-member; upper and lower jaws independently slidably mounted on said member; gripping dogs pivotally mounted in each extremity of each jaw; means for selectively locking a pair of relatively opposite dogs in the two jaws against pivotal movement; a handle pivotally mounted on the body-member; and means associated with the handle for acting on the relatively opposite free dogs when the handle is moved in one direction to throw said dogs in to gripping function and to move the jaws in relatively opposite

directions, and when the handle is moved in the other direction to act on the relatively opposite locked dogs to move the jaws in relatively opposite reverse directions and 5 slip the dogs.

3. A tongs comprising a body-member; upper and lower jaws independently slidably mounted on said member; a gripping dog pivotally mounted in one extremity of 10 one jaw; and a gripping dog pivotally mounted in the opposite extremity of the other jaw; a fixed abutment in the other end of the first jaw and a fixed abutment in the other end of the second jaw; a handle 15 pivotally mounted on the body-member; and contact lugs on the handle one above and the other below its pivotal point, said lug acting, when the handle is moved in one direction, to set the relatively opposite 20 dogs in to gripping function and to move the jaws in relatively opposite directions, and when reversed, to act against the fixed abutments to move said jaws in relatively opposite reverse directions and slip the dogs.

25 4. A tongs comprising a body-member; upper and lower jaws independently slidably mounted on said member; a gripping dog pivotally mounted in each extremity of each jaw; means for selectively locking a 30 pair of relatively opposite dogs in the two jaws against pivotal movement; a handle pivotally mounted on the body-member; and contact lugs on the handle one above and the other below its pivotal point, said 35 lugs acting, when the handle is moved in one direction, on the relatively opposite free dogs to set them in to gripping function and to move the jaws in relatively opposite directions, and when reversed, to act against 40 the relatively opposite locked dogs to move the jaws in relatively opposite reverse directions and slip the dogs.

5. A tongs comprising a body-member; upper and lower jaws independently slidably mounted on said member; a gripping dog pivotally mounted in each extremity of each jaw, each dog having a shank housed in the jaw; means for selectively locking a 45 pair of relatively opposite dogs in the two jaws against pivotal movement; a pair of supplementary gripping jaws; means for pivoting said pair of gripping jaws to a pair of gripping dogs in position to enable said jaws to embrace a pipe and to turn 50 back into the main jaws into contact with the shanks of the dogs thereof; a handle pivotally mounted on the body-member; and means associated with the handle to act through the shanks of the dogs to set the 55 supplementary jaws in to gripping function, and to move the main jaws in relatively opposite directions both forward and reverse.

6. A tongs comprising a body-member;

upper and lower jaws independently slidably mounted on said member; a gripping dog pivotally mounted in each extremity of each jaw, each dog having a shank housed in the jaw; means for selectively locking a 65 pair of relatively opposite dogs in the two jaws against pivotal movement; a pair of supplementary gripping jaws; means for pivoting said pair of gripping jaws to a pair of gripping dogs in position to enable 70 said jaws to embrace a pipe and to turn back into the main jaws into contact with the shanks of the dogs thereof; a handle pivotally mounted on the body-member; and means associated with the handle to act through the shanks of the dogs to set the 75 supplementary jaws in to gripping function, and to move the main jaws in relatively opposite directions both forward and reverse, said means comprising devices on the handle one above and the other below its 80 pivotal point.

7. A tongs comprising an arcuate body-member; an upper and a lower jaw arcuate on substantially the same radius as said body-member and approximately semicircular in length, said jaws being slidably mounted on the body-member and adapted to move in a circular path thereon; gripping jaws pivotally mounted in each extremity of each jaw; means for selectively 95 locking a pair of relatively opposite dogs in the two jaws against pivotal movement; a handle pivotally mounted on the body-member; and means associated with the handle and acting on the dogs, for setting in to 100 gripping function the pair of free dogs and moving the jaws in relatively opposite directions upon the movement of the handle in one direction, and for reversing in relatively opposite directions the movement of 105 the jaws and slipping the dogs when the movement of the handle is reversed.

8. A tongs comprising an arcuate body-member; an upper and a lower jaw arcuate on substantially the same radius as said 110 body-member and approximately semicircular in length, said jaws being slidably mounted on the body-member and adapted to move in a circular path thereon; gripping jaws pivotally mounted in each extremity of each jaw; means for selectively locking a pair of relatively opposite dogs in the two jaws against pivotal movement; a handle pivotally mounted on the body-member; means associated with the handle 115 and acting on the dogs, for setting in to gripping function the pair of free dogs and moving the jaws in relatively opposite directions upon the movement of the handle in one direction, and for reversing in relatively opposite directions the movement of 120 the jaws and slipping the dogs when the movement of the handle is reversed; and a 125

pair of arcuate supplementary gripping jaws adapted to receive and embrace the work, said jaws being pivotally carried by a pair of main jaws, and adapted to fold 5 inwardly therein into operative contact with the dogs of said main jaws.

In testimony whereof I have signed my

name to this specification in the presence of two subscribing witnesses.

LERoy L. RICHARD.
